UNITED STATES PATENT OFFICE.

HENRY STREIFF, OF ST. LOUIS, MISSOURI.

DESIGN FOR A STOPPER-EXTRACTOR.

SPECIFICATION forming part of Design No. 27,892, dated November 23, 1897.

Application filed October 11, 1897. Serial No. 654,884. Term of patent 14 years.

To all whom it may concern:

Be it known that I, HENRY STREIFF, a citizen of the United States, residing at St. Louis, State of Missouri, have invented a new and 5 original Design for a Stopper-Extractor, of which the following is a specification.

This invention relates to a new and original design for a stopper-extractor; and it has for its object to provide a design of this character that shall be both useful and ornamental.

The leading feature of the design resides in a body provided at one end with a triangularly-shaped portion and a narrow hook extension projected from the apex of said triangularly-shaped portion.

A minor feature of the design may be stated to be the provision of a flat elongated body having its side edges inclined and curved into the triangularly-shaped portion and provided 20 at the end opposite said triangularly-shaped portion with a rounded laterally-deflected portion having a circular opening therein.

Another minor feature is in having the hook extension round and curved laterally at an 25 obtuse angle from the body; but it will be understood that this and the other minor features of the design are susceptible to change and modification without affecting the leading feature recited above.

30 In the drawings, Figure 1 is a perspective

view of a stopper-extractor embodying the herein-described design. Fig. 2 is a plan view. Fig. 3 is a side edge view.

Referring to the accompanying drawings, the numeral 1 designates an elongated flat 35 body forming the handle or shank portion of the extractor, and said flat elongated body is provided at one end with a triangularly-shaped portion 2, and with inclined side edges 3, which are curved at the point 4 into the 40 widest part of the triangular portion 2. At the apex of the triangularly-shaped portion 2 the body 1 is provided with a narrow round hook extension 6, curved laterally at an obtuse angle from the body, and at the end opposite 45 said hook extension 6 the body 1 is further provided with a rounded laterally-deflected portion 7, having a circular opening 8 therein.

Having thus described the invention, what 50 I claim is—

The design for a stopper-extractor herein shown and described.

In testimony that I claim the foregoing as my own I have hereto affixed my signature in 55 the presence of two witnesses.

HENRY STREIFF.
